UNITED STATES PATENT OFFICE.

THEODOR DRUZBACH, OF NEW DURHAM, NEW JERSEY.

AMUSEMENT DEVICE.

Application filed June 13, 1921. Serial No. 477,223.

To all whom it may concern:

Be it known that I, THEODOR DRUZBACH, a citizen of Germany, and resident of New Durham, in the county of Hudson and State 5 of New Jersey, have invented certain new and useful Improvements in Amusement Devices, of which the following is a specification.

The present invention relates to amusement devices, and has for its main object to provide a simple and inexpensive contrivance for producing the representation of a human face when mounted upon the back of the hand of the entertainer.

Another object of the invention is to provide a device of this type which is simple in operation and capable of manufacture on a commercial scale, or in other words one which is not so difficult to produce as to be 20 beyond the reasonable cost of an amusement device.

With these and other objects in view, which will more fully appear as the nature of the invention is better understood, the 25 same consists in the combination, arrangement and construction of parts hereinafter described, pointed out in the appended claim and illustrated in the accompanying drawings, it being understood that many 30 changes may be made in the size and proportion of the several parts and details of construction, within the scope of the appended claim, without departing from the spirit or sacrificing any of the advantages of the invention.

Two of the many possible embodiments of the invention are illustrated in the accompanying drawings, in which:—

Figure 1 is a perspective view of a device 40 constructed in accordance with the present invention; Fig. 2 is a side elevation thereof; Fig. 3 is a perspective view illustrating the mode of operation of the device; Fig. 4 is a perspective view of a modified construction; and Fig. 5 is a side elevation of the device shown in Fig. 4.

Referring now first to Figs. 1 to 3, inclusive, of the drawings, the device consists of a base 10, preferably a U-shaped member, 50 upon the free ends of the legs of which are formed the representations 11 of the eyes of a human face. In parallel relation to and centrally between the legs of the U-shaped member is formed a projection 12, 55 that is located in the plane of the U-shaped

member and carries the representation 13 of the nose of a human face, said nose extending at right angles to the general plane of the U-shaped member, as clearly shown in the several figures of the drawings. The 60 device described may be made of any suitable material, suitably painted, for instance in flesh color.

In use, the U-shaped member 10 is inserted between and gripped by the middle- 65 and ring-fingers of the hand (Fig. 3), the representations 11 of the eyes and the representation 13 of the nose appearing upon the back of the hand. A bunch of hair or similar material 14 is then inserted between 70 and gripped by the ring- and little-fingers, after which a piece of fabric 15, such as a handkerchief, is wrapped partly around the hand (Fig. 3), whereby a very effective representation of a human face is produced, the 75 gap between the middle-finger and the fore-finger of the hand representing the mouth of the face and the fore-finger itself the chin portion thereof.

The device illustrated in Figs. 4 and 5 80 of the drawings differs from the one above described in that, instead of a U-shaped base member, an H-shaped base member 16 is provided, carrying two sets of eyes 17 and 18, with which co-operate noses 19 and 20, respectively. One set of eyes and the nose 85 co-operating therewith may be of a color differing from that of the other set of eyes and nose.

When using this device, one set of eyes 90 and the corresponding nose will appear on the back of the hand of the entertainer, and the other set of eyes and its nose on the palm-side of the hand. In this manner the representation of two different faces may 95 be obtained, the change being made quickly by shifting the piece of fabric, for instance the handkerchief, from one side of the hand to the other side.

It is obvious that, while herein U-shaped 100 and H-shaped base members have been described, bases of any other configuration may be made use of, without departing from the invention. There may be used for instance a plate member, to one edge of which are attached representations of eyes and a nose in case a simple device of the character shown in Figs. 1 and 2 of the drawings is 105 to be provided, or representations of eyes and noses may be attached to or may extend 110

from opposite edges of the plate member, in case a device of the character shown in Figs. 4 and 5 is to be produced.

What I claim is:—

5 An amusement device comprising an **H**-shaped base member, a set of eye members on one set of the free ends of the legs thereof, a set of eye members upon the opposite free ends of the legs of said member, and a

nose element associated with each set of eye members, said nose elements extending between the respective eye members at right angles to the general plane of said base member.

Signed at New York, in the county of 15 New York and State of New York, this 28th day of May, A. D. 1921.

THEODOR DRUZBACH.
